UNITED STATES PATENT OFFICE.

THOMAS H. COSTELLO, OF CHICAGO, ILLINOIS; ROSE M. COSTELLO AND WILLIAM E. COSTELLO, EXECUTORS OF SAID THOMAS H. COSTELLO, DECEASED, ASSIGNORS TO ROSE M. COSTELLO, TRUSTEE.

FRICITION HINGE.

Application filed June 4, 1920, Serial No. 386,643. Renewed June 19, 1925.

My invention relates to friction hinges for in either direction will not vary the tension movable stands in which a display panel is 55
rotatively mounted by means of pivot
hinges or trunnions between a plurality of
suspending members. The general structure
which is the subject of my invention
may be illustrated by that of a movable
black-board in which the board on which
the chalks are applied is suspended between
10 two uprights and adapted to be rotated to
change the inclination thereof or to display
alternatively one or the other of the two
faces.

When such devices are set for use, it is
15 necessary that the pivotal connection shall
be adapted to be tightened so that the board
or panel shall retain a rigid position rela-
tively to the supports while in use or while
work is being done thereon. This tension
20 has usually been provided by screw threaded
bolts, passing through the supports and tak-
ing into screw threaded members rigidly at-
tached to the swinging frame, hand pieces
being provided for tightening or loosening
25 the bolts. The objectionable feature of this
construction consists in the fact that, when
the ordinarily right-handed screw threaded
pivots are tightened to give sufficient tension,
a partial revolution of the panel to change
30 the angular inclination thereof or to dis-
play the other face causes the bolt at one
end to loosen and the bolt at the other end
to tighten, a condition which causes uncer-
tain adjustment and frequently results in
35 breaking the apparatus and tearing the
panel from its supports.

It is one object of my invention to provide
simple, cheap, and efficient means for piv-
otally securing a display board or panel up-
40 on a supporting frame in such manner that
it may be readily turned to any angle of
inclination upon the pivot hinges, or rotat-
ed to display either side as desired; it is a
further object of my invention to provide
45 pivot hinges or trunnions for the board or
panel, which may be detachable from each
other whereby the board or panel may be
connected or detached from the supports,
and to provide a hinge or trunnion, the parts
50 of which may be adjusted in frictional or
clamping engagement at any degree of ten-
sion and in which the parts are so positively
held in such relation, that relative rotation

55
The principles of my invention are illus-
trated in the drawing in which Fig. 1 is a
front elevation of a black-board, pivotally
mounted upon supporting standards. Fig.
60 2, is an enlarged vertical section of one of
the hinges or trunnions. Fig. 3 is a section
on the line 3—3 of Fig. 2. Fig. 4 is a
section on the line 4—4 of Fig. 2.

65
Referring to the drawings in which like
characters of reference denote like parts
throughout, a black-board panel is repre-
sented by the letter A and it is supported
upon a pair of standards 5, 5 by means of
70 pivot hinges, each of which is represented
as a whole by the letter B. Below the black-
board the standards are detachably con-
nected by a cross-bar or chalk-rail 7 having
at each end thereof angle brackets 8.

75
Each of the hinges or trunnions B in-
cludes a relatively stationary member 10,
which is mounted on the standard 5 and a
member 11 rotatably movable relatively
thereto, secured to the board or panel A; and
80 provided with flanges 12 by which the at-
tachment by means of the screws is rein-
forced and strengthened. The relatively sta-
tionary and movable hinge members are re-
ciprocally formed to co-act with each other,
85 and may be given the relative forms shown
in Fig. 2 in which 10 is provided with an
annular flange 13, adapted to rest upon the
annular ledge 14. An elongated head 15
provided if desired, which will seat in the
90 bottom of the cup 16 formed by flange 13.
But the relative form and proportions of
these parts is immaterial, it being under-
stood that their proximate faces are adapted
95 to co-act with each other and that openings
18 and 19 extend axially through said parts
in alinement with each other and are alined
and adapted to be alined with a correspond-
ing opening 20, extended through the up-
right 5. A wear plate 22 having an opening
23 should be secured on the outer face of up-
right 5. A pivot bolt 25 extends throughout
100 the openings 18, 19, 20 and 23 and may be
secured to the relatively movable member
11 as illustrated in the device shown. This
may be by means of an angular head 26,
seated in a corresponding depression 27, in
105 the relatively rotatable member, but it is

immaterial in what manner it may be so attached and may in fact if so desired be permanently attached thereto by being cast therein as a chill. A clamping plate or washer 28 is irrevolubly mounted on the body of pivot bolt 25 and slideable thereon. In order that it shall be secured against rotation, the shaft of said pivot bolt may be angular in cross-section, and the said washer provided with a correspondingly angular opening. The end of said pivot bolt is screw threaded to receive a threaded nut 29 which should be formed integrally with a hand wheel 30.

15 It will thus be seen that, when the hand wheel is turned, the relatively stationary and movable parts 10 and 11 will be drawn into frictional contact with each other to any degree of tension, and that the board or panel A attached to such relatively movable member 11, may be set at any desired degree of inclination or revolved as desired without varying the frictional engagement with the relatively stationary member 10.

20 25 I claim:—

1. In a friction hinge; the combination with a relatively stationary member and a relatively rotatable member co-acting therewith and provided with alined openings of 30 a pivot bolt attached to and rotating with said last named member extending through said alined openings, a clamping plate adjustably slideable and relatively non-revolubly mounted on said bolt, and means for adjustably positioning said clamping plate on said bolt.

2. In a friction hinge; the combination with a relatively stationary member and a relatively rotatable member co-acting therewith and provided with alined openings, of 40 a pivot bolt having an angular body portion attached to and rotating with said last named member extending through said alined openings, a clamping plate having an angular opening slidably mounted on said angular body portion of said bolt, and means for adjustably positioning said clamping plate on said bolt.

3. In a friction hinge; the combination 50 of a relatively stationary member and a relatively rotatable member, said relatively stationary and rotatable members being provided with reciprocally formed co-acting parts and provided with alined openings, a pivot bolt attached to and rotating with said last named member extending through said alined openings, a clamping plate slideably and relatively non-revolubly mounted on said bolt, and means for adjustably positioning said clamping plate on said bolt.

4. In a friction hinge; the combination of 60 a relatively stationary member a relatively rotatable member co-acting therewith having an angular recess, a pivot bolt having

an annular head seated in said recess and having an angular body portion and a screw threaded end extending through said alined openings, a clamping plate having an angular opening slidably mounted on said angular body portion, and a nut to adjustably position said clamping plate on said bolt. 70

5. In a friction hinge; a relatively stationary hinge member and a bearing plate provided with openings adapted to be alined with each other, a pivot bolt rotatable in said alined openings, a hinge member secured to said pivot bolt to frictionally engage with the first named hinge member, a clamping plate non-revolubly secured to the pivot bolt to engage said bearing plate, and a nut on the pivot bolt to give longitudinal movement of the clamping plate on said bolt. 75

6. In a friction hinge the combination of 80 co-acting relatively stationary and rotatable members, a pivot bolt secured to the rotatable member against rotation relative thereto and extending through the stationary member, a clamping piece longitudinally slideable and non-rotatable on the pivot bolt, and means for giving relative movement of said rotatable member and said clamping piece toward each other. 85

7. In a pivot hinge; a plurality of members adapted to be secured in rigid relation to each other and provided with alined openings, a shaft rotatably passing through said openings, a rotatable head mounted on one end of said shaft and frictionally engageable with one of said first named members, a washer longitudinally slideable and non-revolubly mounted on the other end of said shaft to engage with the other one of said first named members, and a threaded device 100 to move said washer on said shaft. 95

8. In a friction hinge; a pair of clamping members, one of which is movable relative to the other member, said clamping members being arranged in telescopic relation, a support for the clamping member, a pivot bolt passing non-revolubly through the movable member and revolubly through the immovable member and support, and means on the pivot bolt to co-act with such support and give longitudinal movement to the pivot bolt so as to hold the frictional faces in adjustably operative relation. 110

9. In a friction hinge; a pair of clamping members, one of which is movable relative to the other member, said clamping members being arranged in telescopic relation, a support for the clamping members, a wear plate and a clamping washer mountable on said support on the side opposite to the said clamping members, a pivot bolt passing non-revolubly through the movable member and the clamping washer and passing revolubly through the immovable member and the wear plate, and means on the pivot bolt for 115 120 125 130

moving said clamping member and said clamping plate relatively to each other so that the frictional faces of the clamping members may be in adjustably operative relation.

10. In a friction hinge; a pair of clamping members one of which is movable relative to the other member, said clamping members being arranged in telescopic relation, a support for the clamping members, a wear plate and a clamping washer mountable on said support on the side opposite to the said clamping members, a pivot bolt having a squared head seated in the movable

member and a body portion passing non-revolubly through the clamping washer, and further passing revolubly through the immovable member and the wear plate, and means on the pivot bolt for moving said clamping member and said clamping plate relatively to each other so that the frictional faces of the clamping members may be in adjustably operative relation.

In witness whereof, I have hereto set my hand at Chicago, Illinois, this 29th day of May, 1920.

THOMAS H. COSTELLO.
